UNITED STATES PATENT OFFICE.

SIDNEY HOWE SHORT, OF CLEVELAND, OHIO.

THIRD RAIL FOR ELECTRIC RAILWAYS.

SPECIFICATION forming part of Letters Patent No. 605,261, dated June 7, 1898.

Application filed November 5, 1897. Serial No. 657,511. (No model.)

To all whom it may concern:

Be it known that I, SIDNEY HOWE SHORT, a citizen of the United States, residing at Cleveland, in the county of Cuyahoga and State of Ohio, have invented a new and useful Third Rail for Electric Railways, of which the following is a specification.

This invention relates to third rails for electric railways.

10 The object of the invention is to provide an arrangement of third or contact rail for electric railways whereby accidental short-circuiting of current therefrom is provided against, wherein danger to persons walking over the road-bed is avoided, wherein the rail is efficiently supported and insulated, and whereby the contacting surface of the rail is protected in a measure from rain, snow, sleet, and the like.

20 Further objects of the invention will appear more fully hereinafter.

The invention consists, substantially, in the construction, combination, location, and arrangement of parts, all as will be more fully 25 hereinafter set forth, as shown in the accompanying drawings, and finally specifically pointed out in the appended claims.

In the accompanying drawings, Figure 1 is a transverse sectional view of the road-bed, 30 parts in the side elevation showing the application of my invention. Fig. 2 is a similar view of a slightly-modified arrangement.

Reference-sign A designates a cross tie or sill of the road-bed, B the traction or service 35 rails, and C the third or contact rail. In the form shown in Fig. 1 this rail comprises an I-beam and is supported upon a short transverse bar D. This bar carries or is formed with inverted cup or bell shaped castings E 40 at the end thereof, adapted to receive therein a suitable insulating material F—such, for instance, as rubber, wood, sulfur, or the like. The bar D is supported upon uprights or standards G, suitably mounted on or secured 45 to the cross ties or beams A, and the upper ends of said uprights or standards are received and embedded in the insulating material contained in the bell or cup shaped castings E.

50 In order to protect in a measure the contact-surface of the third rail from rain, snow, sleet, and the like and to avoid danger of

short-circuiting the current therefrom to a grounded part of the road-bed or structure by a workman carelessly resting a tool, bar, 55 or other article thereagainst, as well as to protect workmen or other pedestrians walking over or along the road-bed or structure from danger of receiving a shock by coming in contact with a live conductor, I provide a 60 cap or covering H of suitable insulating or non-conducting material for the third rail. This cap or covering H may be in the form of a board or strip resting upon the top surface of the third rail, as clearly shown, with 65 the edges thereof projecting beyond and over the edges of the top surface of the third rail. The sides or surfaces J of the third rail constitute the contact-surface against which operate the shoes or other contact-making devices carried by the car or trucks. From this 70 description it will be seen that not only is the contact-surface of the conducting or third rail measurably protected from rain, sleet, snow, and the like and the danger of short- 75 circuiting or of shocking workmen or pedestrians avoided, but an efficient contact between the rail and the shoe or other collector carried by the car is assured by reason of the fact that such shoe or collector operates in 80 the channel or groove formed in the side of the third rail by the flanges and stem of such rail.

In Fig. 2 I have shown a slightly-modified arrangement wherein the third or contact rail 85 C' is in the form of a channel-bar placed edge-wise. In this form of third rail the contact-shoe or collector travels against the surface J' of the channel-bar, and it will be noted that the same advantages of an efficient contact are secured in this form as in the form employing an I-beam, as in Fig. 1, for the reason that the contact-shoe or collector travels in the channel or groove of the beam C' in the same manner as it does in the channel 90 or groove formed in the side of the I-beam. In the form shown in Fig. 2 I have also shown a slightly-modified arrangement for supporting the conducting-rail, wherein I suitably attach or secure to the back of the rail C' a 100 hollow casting E', which casting is adapted to be filled with a suitable insulating material F, the same as in the case of bell or cup shaped castings E of Fig. 2, and the uprights

or standards G are arranged to project into the open end of said hollow casting and to be embedded in said insulating material, thereby efficiently supporting and insulating the third rail from the road-bed or structure.

Of course it will be readily understood that the particular location of the third rail relative to the traction or service rails is unimportant and forms no part of the present invention. For instance, the third rail may be located between the service-rails, as shown in full lines, Figs. 1 and 2, or alongside but outside of such rails, as indicated in dotted lines in Fig. 2.

While my invention is particularly designed for use in connection with elevated-railway work, it may also be employed generally in electric-railway constructions.

Many changes and modifications in the specific details of construction and arrangement may readily suggest themselves to persons skilled in the art and still fall within the spirit and scope of my invention. I do not desire, therefore, to be limited to the exact details of construction and arrangement shown and described; but,

Having now set forth the object and nature of my invention and a form of apparatus embodying the same, what I claim as new and useful and of my own invention, and desire to secure by Letters Patent of the United States, is—

1. In an electric railway the combination with standards, a bar supported by but insulated from said standards, a third or contact rail supported upon said bar, said rail presenting a side surface for contact with the shoe or collector, and a strip or plate laid

lengthwise upon said rail and extending over the top edges thereof, as and for the purpose set forth.

2. In an electric railway the combination with standards, a bar supported by but insulated from said standards, a third or contact rail supported upon said bar, said rail provided with a channel or groove in the side thereof extending lengthwise of said rail, and an insulating-plate resting upon the top of said rail, said insulating-plate extending lengthwise of said rail and being of a width greater than that of the rail whereby its edges project over the edges of the rail and form a protecting-cap therefor, as and for the purpose set forth.

3. In an electric railway the combination with standards, a bar carrying inverted-cup-shaped castings at the ends thereof, said castings adapted to be filled with insulation, said standards arranged to project into said castings and to be embedded in the insulation contained therein, a third or contact rail supported by said bar, said rail presenting a side surface for contact with the shoe or collector, and a plate of insulation wider than said rail, said plate resting upon the top surface of said rail and extending lengthwise thereof, thereby forming a protecting-cap for said rail, as and for the purpose set forth.

In witness whereof I have hereunto set my hand, this 1st day of November, 1897, in the presence of the subscribing witnesses.

SIDNEY HOWE SHORT.
